UNITED STATES PATENT OFFICE.

EDWARD GEORGE NICHOLSON, OF HORSELL, WOKING, ENGLAND.

THERMALLY-ACTUATED ELECTRIC SWITCH.

Application filed April 12, 1926, Serial No. 101,534, and in Great Britain April 29, 1925.

This invention relates to thermally actuated switches particularly intended to be used for preventing overheating of electric heating apparatus, of the kind in which a spring mechanism tending to open the switch is normally held out of operation by fusible alloy or solder which melts or softens when a certain predetermined temperature is reached.

10 By way of example two embodiments of the invention are illustrated in the accompanying drawings, in which—

Figure 1 is a plan view from below of the first embodiment.

15 Figure 2 is a side view in section of Figure 1.

Figure 3 is an end view, half in section on the line I—I of Figure 1.

20 Figure 4 is a plan view from below of the second embodiment.

Figure 5 is a side view in section of Figure 4, and

Figure 6 is an end view in section on the line II—II of Figure 4.

25 Referring first to Figures 1 to 3, a heating element in two sections 1 and 2 is mounted on the true bottom 3 of a heating appliance and may be enclosed, together with the switch, by a false bottom (not shown).

30 The sections 1, 2, are respectively connected to one of the supply plugs 4, 5, and are provided at their opposite ends with connecting contacts 6, 7. The circuit is normally completed by a bridging spring 8 which is secured to a frame 9 having a tooth 10 engaging a ratchet wheel 11 normally secured on to its spindle 12 by a suitable fusible solder or alloy. The spindle is mounted in close contact with the bottom 3 so that it

35 attains as nearly as possible the same temperature as the appliance. The frame 9 may be conveniently guided by making the contact 7 longer or more extended than the contact 6, as shown in Figure 1. This tends 40 to tilt the frame so as to keep the tooth 10 in engagement with the wheel 11. A pin 13 provided with a setting button 14 operable from the outside of the appliance is fastened to the frame 9 and a spring 15 acts

45 to move the spring 8 out of engagement with the contacts 6, 7. If the temperature of the appliance rises beyond a predetermined limit the solder or alloy melts, thus allowing the ratchet wheel 11 to rotate and the spring 50 55 therefore draws the spring 8 out of engagement with the contacts 6, 7 thus break-

ing the circuit. The straight edge of the part of the frame 9 adjacent to the tooth 10 causes the tooth to come entirely out of engagement with the wheel after it has moved a short distance and before the circuit is opened. This ensures a clean and rapid break of the circuit in spite of any sluggishness in rotation of the wheel, and allows the ratchet wheel to stop rotating as soon as possible. As soon as the temperature has fallen sufficiently the solder or alloy sets and secures the wheel and the switch can be re-set by pressing the button 14. If desired the resetting button 14 may be enclosed within the switch chamber.

Referring now to Figures 4 to 6 the switch comprises a rotating switch bar 16 which bridges a pair of contacts 17, 18. The ratchet wheel 19 is formed on a sleeve 20 soldered to the fixed spindle 25. This sleeve 20 forms a journal for the bar 16 which carries a pawl 26 in engagement with the ratchet wheel. A spring 21 operates the switch. In order to ensure a rapid break despite sluggish action of the ratchet wheel a cam 22 is secured on the spindle 25 and the pawl is broadened to ride on the cam which lifts the pawl out of engagement with the ratchet wheel after the bar has moved a short distance but before it has left the contacts. The switch may be reset by a spring button and connecting link or push rod (not shown) arranged to be operable from outside or not as desired.

50 The ratchet member may be provided with a spring back stop of the usual kind in order to ensure that it always stops with the teeth in a certain definite position so that the switch when reset always takes the same position. This is not essential, however, since the range of engagement of the switch blade with the contacts will cover any variation in the stopping position of the ratchet member. Finally, more than one switch blade and more than two contacts may be used where desired, and the switch may if desired be mounted in a separate chamber from the heating element.

What I claim is:—

1. In a thermally actuated switch of the kind set forth, a ratchet member normally held by a fusible alloy, a spring actuated part, a pawl on said spring actuated part co-acting with said ratchet member, and a guide member co-operating with said ratchet member for positively raising said pawl out

of engagement with said ratchet member after a short movement of said spring actuated part when said alloy fuses.

2. In an electrically heated appliance, a thermally actuated switch, comprising a spindle secured in good thermal contact with the heated part of the appliance, a ratchet wheel revolubly mounted on said spindle and normally secured thereto by a fusible alloy, a frame having a tangential edge embracing said ratchet wheel, a pawl in said tangential edge of said frame, a spring contact bridge secured to said frame, a pair of contacts

forming a break in the heater circuit positioned so as to tilt the frame so that its said tangential edge contacts with, and its pawl engages, said ratchet member, when said contact bridge bears on said contacts to complete the circuit, a resetting bar on said frame extending outside the appliance, and spring means tending to move said bridge out of contact with said contacts.

In testimony whereof I have signed my name to this specification.

EDWARD GEORGE NICHOLSON.
